UNITED STATES PATENT OFFICE.

CLARENCE W. COLEMAN, OF WESTFIELD, NEW JERSEY, ASSIGNOR TO THE
HALL SIGNAL COMPANY, A CORPORATION OF MAINE.

CAR-CONTROLLING APPARATUS.

No. 845,161.

Specification of Letters Patent.

Patented Feb. 26, 1907.

Application filed June 17, 1905. Serial No. 235,674.

To all whom it may concern:

Be it known that I, CLARENCE W. COLEMAN, a citizen of the United States, and a resident of Westfield, Union county, State of New Jersey, have invented certain new and useful Improvements in Car-Controlling Apparatus, of which the following is a specification.

This invention relates to new improved apparatus for automatically controlling the movement of a car.

The invention seeks to provide an arrangement whereby the car may be automatically stopped or have its speed checked or be otherwise controlled when the track in advance is in a condition of danger.

It also seeks to accomplish its result by means which are simple in construction and effective in operation.

20 In the accompanying drawings, forming part of this specification, the invention is shown in association with a locomotive.

Figure 1 shows diagrammatically the invention as applied to a railway. Fig. 2 shows a detail. Fig. 3 shows a detail of a modification.

Referring now more particularly to the invention as specifically shown in the drawings, 1 is a locomotive provided with an ordinary air-brake system.

2 and 3 are respectively the steam and air-brake valves.

4 is a compressed-air pipe leading to the piston-cylinders 5 and 6, which latter are 35 connected with the valve-levers 2 and 3, respectively, so that when air-pressure is admitted to the cylinders 5 and 6 levers 2 and 3 will be moved forward to shut off the steam and apply the air-brakes. Connected in

40 the pipe 4 is a controlling-valve 7, operated by controlling-magnet 8. This magnet is located on the locomotive or engine and is included in a circuit connected with battery 9 and switch 10. Referring to the switch, 45 10, 11, and 12 are metal guides fixed on the car and in which works the wooden bar 13. This bar 13 carries a metal angle-plate 14, adapted to make electrical connection with the contact-points 15 and 16 on the guides 11 and

50 12. 17 are brushes pivoted to the plate 14 and projecting downward therefrom. These brushes are provided with springs 18, which hold them in an inclined position and against their stops 19. 20 and 21 are springs which

hold the reciprocating bar 13 in its lower position, so that plate 14 will make electrical connection with contacts 15 and 16, these springs permitting the bar 13 to move upward, so as to break this electrical connection at contacts 15 and 16. 22 is a circuit-wire 60 leading from one side of battery 9 through magnet 8 to metal plate 14 of the switch 10. Circuit-wire 23 leads from the other side of the battery to guides 11 and 12. 24 is a branch wire leading from wire 23 to one of the 65 car-axles. In ordinary cases the metal frame of the car or engine would take the place of wire 24.

25 is a hand-switch connected with wires 26 and 27, which are in turn connected to 70 wires 22 and 23. This switch 25, if desired, may be connected, as shown, with a whistle 28 or other signal, so that when the switch 25 is operated the signal will be given.

In the preferred arrangement of the apparatus the circuit through magnet 8 is normally closed at the switch 10 and magnet 8 is normally energized. This is the arrangement shown in the drawings. When the magnet is thus normally energized air-pressure in 75 the pipe 4 is cut off from cylinders 5 and 6, thereby permitting steam to be supplied to the engine and shutting off the air-brakes. When magnet 8 is de-energized, as by breaking its circuit, air-pressure through the pipe 80 4 enters cylinders 5 and 6 to shut off the steam and put on the air-brakes.

The track is divided into insulated sections 29, 30, and 31.

32 is a track-magnet, and 33 a track-battery of the track-circuit which includes the rails of section 30.

34 is a track-magnet, and 35 a track-battery of a track-circuit which includes the rails of section 31.

36 is a signal for section 30, operated by suitable means, including the circuit-controller 37, which is operated by magnet 32.

38 is the signal for section 31, operated by suitable means, including the circuit-controller 39, which is operated by magnet 34.

40 is a track-contact or third rail, which extends a suitable distance along the track. Under ordinary conditions there would be one of these track-contacts for each section of the 105 track. These track-contacts may be from fifty to one hundred feet in length, more or less.

41 is a branch circuit including the circuit-controller 42 and having one end connected to track-contact 40 and its other end connected to one of the rails of section 30. Circuit-controller 42 is connected to the up-and-down rod 43 of section 38, so as to be operated thereby.

The operation of the apparatus is as follows: When the engine is running along the track and before it reaches track-contact 40, switch 10 is closed by having its plate 14 resting on contacts 15 and 16. The circuit through magnet 8 is therefore closed and the magnet is energized, so that steam is supplied from the boiler of the engine and the air-brakes are cut off. When the train reaches the track-contact 40, the brushes 17 strike the contact 40, so as to make an electrical connection with it and at the same time elevate the plate 14 above contacts 15 and 16. This breaks the magnet-circuit at these contact-points, but switches into the magnet-circuit the branch circuit 41. At this time the circuit extends from battery 9, through wires 23 and 24, to the car-wheel, track-rail of section 30, the branch circuit 41, track-contact 40, brushes 17, wire 22, and magnet 8, back to battery. If track-section 31 is in a condition of safety, its signal 38 will be at "safety" and circuit-controller 42 will be closed. Hence magnet 8 will still be energized, and the progress of the train will not be interfered with. On the other hand, if track-section 31 is occupied by a train or is otherwise in a condition of danger the signal 38 will be at "danger" and circuit-controller 42 open. In this case magnet 8 will be deenergized to shut off the steam and put on the air-brakes. If for any reason the engineer does not wish his train to be stopped by the danger condition of signal 38 or by the danger condition of track-section 31, he may operate switch 25, thereby closing the circuit of battery 9 through magnet 8 and wires 26 and 27. This will keep magnet 8 still energized and prevent the application of the air-brakes and the shutting off of steam-pressure. This movement of the switch 25 also operates whistle 28.

It will be observed that the progress of the train is automatically controlled from the section in advance of the train. It will also be observed that the use of a controlling-magnet normally energized is especially advantageous, inasmuch as a failure of the apparatus to work properly would deenergize the magnet and stop the train. In other words, errors would be on the side of safety.

In Fig. 3 the magnet 8 is shown as employed to operate a signal on the car. 44 and 45 are electric lamps, the latter being preferably red in color and connected in circuit with generator 46 and circuit-controller 47, operated by magnet 8. When magnet 8 is energized, lamp 45 is cut into circuit and

lamp 44 is cut out. When magnet 8 is deenergized in the manner heretofore described, lamp 45 is cut out and lamp 44 is cut into circuit at its circuit-controller 46 to warn the operator on the car. If desired, the control of the car may be accomplished by means of the signals such as 44 and 45 and without the means for automatically stopping the car. Such an arrangement would be novel and useful and within the scope of the invention. Instead of lamp 45 a whistle may be used to sound when magnet 8 is deenergized.

It is to be understood that the present invention is applicable to cars propelled by electricity or any other motive power. It is also to be understood that this invention is not limited to the precise details in structure or arrangement herein specifically shown and described. These may be widely varied without departing from the scope of the invention.

What I claim, and desire to secure by Letters Patent, is—

1. In a car-controlling system a track comprising an insulated section; a track-circuit for said section comprising a track-battery, the opposite rails of the section, and a track electromagnetic device; a car provided with automatic controlling means; a magnet on the car for operating said controlling means; a circuit for said magnet; and a circuit branch arranged to be connected in the magnet-circuit when the car has reached a predetermined point on the track, said circuit branch being controlled by said electromagnetic device of the track-circuit.

2. In a car-controlling system a track comprising an insulated section; a track-circuit for said section comprising a track-battery, the opposite rails of the section, and a track electromagnetic device; a car provided with automatic controlling means; a magnet on the car for operating said controlling means; a normally closed circuit for said magnet; and a circuit branch arranged to be connected in the magnet-circuit when the car has reached a predetermined point on the track, said circuit branch being controlled by said electromagnetic device of the track-circuit.

3. In a car-controlling system a track comprising an insulated section; a track-circuit for said section comprising a track-battery, the opposite rails of the section, and a track electromagnetic device; a car provided with automatic controlling means; a magnet on the car for operating said controlling means; circuit connections for said magnet; and a circuit branch arranged to be connected in circuit with said magnet when the car has reached a predetermined point on the track preceding said section, said circuit branch being controlled by said electromagnetic device of the track-circuit.

4. In a railway signaling and car control-

nal of a track-section in advance of said point; and a hand-switch on the car for controlling said magnet.

13. In a railway-car-controlling system, the combination of a track divided into sections, both rails of each section being insulated from the rails of an adjoining section; a section-circuit including both rails of a section; a car provided with automatic controlling means; a magnet on the car for operating said controlling means; a circuit including said magnet; and a circuit branch including a rail of the track arranged to be included in the magnet-circuit when the car has reached a predetermined point on the track, said circuit branch being controlled by a section-circuit of a track-section in advance of said point; and a hand-switch on the car for controlling said magnet.
14. In a railway-car-controlling system, the combination of a track divided into sections; a car provided with automatic controlling means; a single magnet on the car for operating said controlling means; a circuit including said magnet; a switch on the car and in said circuit; a branch circuit arranged to be included by said switch in the magnet-circuit when the car has reached a predetermined point on the track, said circuit branch being controlled by a track-section in advance; and a hand-switch on the car for controlling said magnet.
15. In a railway-car-controlling system, the combination of a track divided into sections; a car provided with automatic controlling means; a normally energized magnet on the car for operating said controlling means; a normally closed circuit including said magnet; a switch on the car and in said circuit; and a branch circuit arranged to be included by said switch in the magnet-circuit when the car has reached a predetermined point on the track, said circuit branch being controlled by a track-section in advance; and a hand-switch on the car for controlling said magnet.
16. In a railway-car-controlling system, the combination of a track divided into sec-

tions; a car provided with automatic controlling means; a magnet on the car for operating said controlling means; a circuit including said magnet; a switch on the car and in said circuit; a branch circuit including a rail of the track arranged to be included by said switch in the magnet-circuit when the car has reached a predetermined point on the track, said circuit being controlled by a track-section in advance; and a hand-switch on the car for controlling said magnet.

17. In a railway-car-controlling system, the combination of a track divided into sections; a car provided with automatic controlling means; a magnet on the car for operating said controlling means; a circuit including said magnet; a switch on the car and in said circuit; a track-contact; a branch circuit connected to said track-contact and to a rail of the track; said switch operating to include said branch circuit in the magnet-circuit when the train reaches the track-contact; means for controlling said branch circuit from the track-section in advance; and a hand-switch on the car for controlling said magnet.

18. In a railway-car-controlling system, the combination of a track divided into sections; a car provided with automatic controlling means; a normally energized magnet on the car for operating said controlling means; a normally closed circuit including said magnet; a switch on the car and in said circuit; a track-contact; a branch circuit connected to said track-contact and to a rail of the track; said switch operating to include said branch circuit in the magnet when the train reaches the track-contact; means for controlling said branch circuit from the track-section in advance; and a hand-switch on the car for controlling said magnet.

In testimony whereof I have signed my name to this specification in the presence of two subscribing witnesses.
